(57) **CLAIM**

The ornamental design for an ice machine, as shown and described.

DESCRIPTION

FIG. 1 is a front isometric view of a top, front, and left side of a first embodiment of an ice machine in a first configuration;

FIG. 2 is a front isometric view of a top, front, and right side of the ice machine of FIG. 1;

FIG. 3 is a front elevational view of the ice machine of FIG. 1;

FIG. 4 is an enlarged partial front view of the ice machine of FIG. 1;

FIG. 5 is a left side elevational view of the ice machine of FIG. 1;

FIG. 6 is a right side elevational view of the ice machine of FIG. 1;

FIG. 7 is a top plan view of the ice machine of FIG. 1;

FIG. 8 is a front isometric view of a top, front, and left side of the ice machine of FIG. 1 in a second configuration;

FIG. 9 is a front isometric view of a top, front, and right side of the ice machine of FIG. 8;

FIG. 10 is a front elevational view of the ice machine of FIG. 8;

FIG. 11 is a left side elevational view of the ice machine of FIG. 8;

FIG. 12 is a right side elevational view of the ice machine of FIG. 8;

FIG. 13 is a front isometric view of a top, front, and left side of a second embodiment of an ice machine in a first configuration;

FIG. 14 is a front isometric view of a top, front, and right side of the ice machine of FIG. 13;

FIG. 15 is a front elevational view of the ice machine of FIG. 13;

FIG. 16 is an enlarged partial front view of the ice machine of FIG. 13;

FIG. 17 is a left side elevational view of the ice machine of FIG. 13;

FIG. 18 is a right side elevational view of the ice machine of FIG. 13;

FIG. 19 is a top plan view of the ice machine of FIG. 13;

FIG. 20 is a front isometric view of a top, front, and left side of a third embodiment of an ice machine in a first configuration;

(Continued)

FIG. 21 is a front isometric view of a top, front, and right side of the ice machine of FIG. 20;
 FIG. 22 is a front elevational view of the ice machine of FIG. 20;
 FIG. 23 is an enlarged partial front view of the ice machine of FIG. 20;
 FIG. 24 is a left side elevational view of the ice machine of FIG. 20;
 FIG. 25 is a right side elevational view of the ice machine of FIG. 20;
 FIG. 26 is a top plan view of the ice machine of FIG. 20;
 FIG. 27 is a front isometric view of a top, front, and left side of the ice machine of FIG. 20 in a second configuration;
 FIG. 28 is a front isometric view of a top, front, and right side of the ice machine of FIG. 27;
 FIG. 29 is a front elevational view of the ice machine of FIG. 27;
 FIG. 30 is a left side elevational view of the ice machine of FIG. 27;
 FIG. 31 is a right side elevational view of the ice machine of FIG. 27;
 FIG. 32 is a front isometric view of a top, front, and left side of a fourth embodiment of an ice machine in a first configuration;
 FIG. 33 is a front isometric view of a top, front, and right side of the ice machine of FIG. 32;
 FIG. 34 is a front elevational view of the ice machine of FIG. 32;
 FIG. 35 is an enlarged partial front view of the ice machine of FIG. 32;
 FIG. 36 is a left side elevational view of the ice machine of FIG. 32;
 FIG. 37 is a right side elevational view of the ice machine of FIG. 32; and,
 FIG. 38 is a top plan view of the ice machine of FIG. 32. The dash-dash-dash lines shown in the figures are for the purpose of illustrating environmental structure and form no part of the claimed design.
